WINDOW SHADE

Ellen W. Kingsbury, Rutherford, N. J.

Application July 28, 1937, Serial No. 156,074

2 Claims. (Cl. 156—10)

When a window shade of the well known type, to wit, wound on a spring roller, becomes soiled or worn at its lower or free end, which is formed with a hem to receive the usual stiffening stick, it is not possible to reverse it end for end and use such stick for stiffening the now free end since the latter end would be without the hem to receive the stick. By saying that this is not possible I mean that it is not ordinarily possible of accomplishment by the user, or in the absence of the means, as the proper sewing machine, for forming a reserve hem with a stitch precisely simulating that of the worn or soiled hem or having some other special and of course conventional characteristic.

According to this invention the shade proper is caused initially to be provided with two hems, one at each end, and to one such end of the shade proper means in the form of flexible sheet material, say like that of the shade proper itself, is attached by which to connect to the roller, as by tacking, the completed shade comprising the shade proper and such means.

The said means may be a strip of narrow width but having a length equal to the width of the shade proper.

But whatever its form it is preferably attached to the shade proper with these observations in view: That the attaching line shall be so located as most likely to prevent disruption of the stitching or equivalent attaching medium as an incident of the winding or unwinding of the shade and to insure the shade undergoing winding on the roller without disposition to become inordinately creased or wind irregularly or unduly increase the bulk of the wound mass; and that the attaching shall be so effected, to wit, of the mentioned connecting means to the reserve hem, that at least one ply of such hem shall not be caught by the attaching medium, whereby the reserve hem as to such ply will appear unmitigated when the shade is reversed. Of course, such attaching will usually be by stitching, and in order that such stitching may be readily and quickly removed it is a feature of the invention that stitching is employed that may be readily pulled out, as chain-stitching.

In the drawing,

Fig. 1 is a fragmentary perspective view of a shade-and-roller assembly embodying the invention in its preferred form;

Fig. 2 is a similar view of the material of the shade proper and the strip here forming the said connecting means as they exist when such strip 55 has been attached to such material and before

the reserve hem has been formed in the latter; and

Fig. 3 is an enlarged sectional view in the plane of the chain-stitching line *a* of Fig. 1.

The shade proper is indicated at 1 and may be composed of any suitable flexible sheet material, as the fabric commonly employed for the purpose. It here has one end portion formed with a hem 2, as usual, receiving the stiffening stick 3: the stitching 4 for this purpose is here shown as of the usual zig-zag type.

In carrying out my invention according to the present example the mentioned connecting means is formed by a strip 5 of flexible sheet material, preferably the same as that of the shade proper, 15 being as long as the latter is wide but usually being only a few inches wide. This strip is laid across one face of the shade proper so as to extend parallel with and be suitably distanced from that end edge 1a of the shade proper which is 20 usually tacked to the roller, thus to leave extending beyond it a terminal region 1b of the shade proper (Fig. 2) having sufficient width to form a hem of about the width of the hem 2, whereupon the strip is stitched to the shade 25 proper along a line *a* which will be parallel and close to that long edge of the strip which next adjoins said end edge 1a of the shade proper.

Then a hem 6 is formed in the shade proper 30 simulating the hem 2 but so as to leave the strip 5 of course unenveloped by the hem. This may be done by folding the body portion 1c of the shade proper along a line *b*—*b* parallel and more or less close to the stitching line *a* and then, having lapped inwardly the free end edge of end portion 1b, as at 7, stitching together such end portion and body portion 1b, through such lap, such stitching, as at 8, preferably being conventionally formed in some special pattern, such as that characterizing stitching 4.

When the completed shade has been thus constructed it may be secured to the roller 9 by tacking, as at 10, the free end margin of the strip to such roller, this being preferably done so that, as shown in Fig. 1, the strip will stand outwardly 45 lapping the hem 6. The object in thus assembling the shade with the roller is to present the fold 6a of the hem next to the roller whereby there will be assurance that the shade will wind on the roller without irregularity and the interference with such winding and inordinate creasing which would ensue if the fold 6a were outward of the shade relatively to the roller.

An important feature of my invention is that the connecting means 5 of sheet material laps 55

the reserve hem and in that relation is stitched thereto inasmuch as thereby a strong union between them exists.

Further, the stitching at line *a* being so effected that only the ply of the hem 6 which next adjoins the strip is caught by the stitching, when the strip is removed and the shade has been reversed the other ply will appear unmutilated by the stitching.

10 The stitching at *a* is preferably of some type, which I herein term the "pull-thread" type, which will permit its ready withdrawal as shown by Fig. 3, illustrating chain-stitching; if the end *a'* of the stitching be pulled upon, such stitching may be readily removed or ravelled out only to leave a line of needle holes.

Having thus fully described my invention what I claim is:

1. The herein described assembly comprising a 20 roller, a shade proper of flexible sheet material to be wound on the roller and having each end folded back and thereby forming a stick-receiving hem, and a connecting strip of flexible sheet

material extending transversely of the shade proper and secured to the roller and having one longitudinal marginal portion thereof lapping one ply of one hem and stitched to said ply independently of the other ply of the same hem along a line paralleling and removed from the fold of the latter hem.

2. The herein described assembly comprising a roller, a shade proper of flexible sheet material to be wound on the roller and having each end folded back and thereby forming a stick-receiving hem, and a connecting strip of flexible sheet material extending transversely of the shade proper and secured to the roller and having one longitudinal marginal portion thereof lapping 10 that ply of one hem which will be the relatively outer ply of such hem when the shade is wound on the roller and stitched to said ply independently of the other ply of the same hem along a line paralleling and removed from the fold of 15 the latter hem.

ELLEN W. KINGSBURY.
